United States Patent Office

Des. 179,665
Patented Feb. 5, 1957

179,665

COMBINED SPRAY GUN AND CONTAINER

Robert E. Sykes, Evanston, Ill., assignor to Bell & Gossett
Company, Morton Grove, Ill., a corporation of Illinois

Application December 14, 1954, Serial No. 33,555

Term of patent 14 years

(Cl. D62—2)

The figure is a perspective view of a combined spray gun and container embodying my new design. The side of the combined spray gun and container not illustrated is substantially like that shown except that the knurled, cylindrical nut is omitted on the barrel.

I claim:

The ornamental design for a combined spray gun and container, as shown and described.
